UNITED STATES PATENT OFFICE.

BURROUGH P. MOORE, OF ST. PETERSBURG, FLORIDA.

WRENCH.

1,276,678.

Specification of Letters Patent. Patented Aug. 20, 1918.

Application filed March 2, 1917. Serial No. 152,063.

To all whom it may concern:

Be it known that I, BURROUGH P. MOORE, a citizen of the United States, residing at St. Petersburg, in the county of Pinellas and 5 State of Florida, have invented new and useful Improvements in Wrenches, of which the following is a specification.

This invention relates to wrenches, and especially to that class of wrenches commonly known as monkey wrenches.

The primary object of the invention is the provision of a wrench of the above class which will permit of a quick adjustment of the movable jaw and when so adjusted the 15 said jaw will be positively locked against movement in either direction.

A further object of the invention is the provision of a wrench having a movable jaw capable of being adjusted with the hand 20 holding the wrench, leaving the other hand free for other purposes.

A still further object of the invention is the provision of a wrench of this class wherein the movable jaw is interchangeable, 25 permitting the use of the wrench either as a monkey wrench or pipe wrench.

Other objects and advantages of the invention will appear in the following description when taken in connection with the 30 accompanying drawings, in which:

Figure 1 is a perspective view of a wrench embodying the present invention;

Fig. 2 is a longitudinal sectional view through the same showing a movable jaw in 35 its locked position in full lines, and illustrating the manner of removably securing the handle to the shank;

Fig. 3 is a transverse sectional view taken on a line with the pivot by means of which 40 the dog is secured to the movable jaw; and

Fig. 4 is a detail perspective view of the interchangeable jaw for use when the wrench is employed as a pipe wrench.

Referring in detail to the drawings where- 45 in like characters of reference denote corre-
sponding parts, the numeral 1 denotes the shank of the wrench which is rectangular in cross section and has formed or secured upon its end a stationary jaw 2, this jaw be-
ing of the usual form. Upon the opposite 50 end of the shank there is provided a reduced rounded section 3 having formed thereon threads 4, by means of which the handle 5 may be removably secured.

The movable jaw 6 of the wrench is 55 formed with a sleeve 7, having therein a rectangular opening 8, of a size to have a sliding fit upon the shank 1. Formed in one side of the movable jaw is a slot 9, within which is adapted to operate a dog 10, the 60 said dog being eccentrically pivoted as at 11 in ears 12 formed on the movable jaw. The dog 10 is formed with teeth 13 adapted for engagement with a rack 14 formed upon the side of the shank 1, the said teeth engaging 65 the shank only when the dog is in its closed position, that is, when the finger piece 15 of the said dog is moved inwardly and abuts against the side of the sleeve 7. The sur- 70 face upon which the teeth 13 of the dog are 75 formed is rounded, and by reason of the location of the pivot 11 with respect to this surface, provides a substantially cam rack engagement between the dog and the shank when the said teeth engage the rack 14, it 80 being necessary to insert a slight lifting force upon the underside of the finger piece to disengage the dog for the purpose of adjusting the movable jaw. It will thus be seen that the movable jaw may be quickly 85 and positively locked in any desired position upon the shank 1, against movement in either direction and it is necessary to purposely raise the free end of the dog in order to permit any movement of the jaw.

In order to adapt the wrench for use upon pipes, there is provided an interchangeable jaw 16 formed with an arcuate serrated de- 90 pression 17 for the purpose of gripping the pipe. The other features of this jaw are 95 substantially the same as those of the one previously described. When it is desired to substitute the jaw 16 for the jaw 6 it is only necessary to remove the handle to permit of the removal of the jaw 6, when the jaw 16 95 may be substituted, and the handle again positioned.

From the foregoing description when taken in connection with the accompanying drawings it will be seen that the invention 100 provides a simple, strong and durable wrench capable of quick and positive adjustment, and one that may be used either as a monkey wrench or a pipe wrench.

Having described the invention what I 105 claim is;

A wrench comprising a shank, a station- 100 ary jaw carried thereby, a rack formed on

said shank, a jaw slidably mounted on the shank, said jaw being formed with an opening, spaced ears formed on said jaw upon each side and adjacent one end of said opening, a lever eccentrically pivotally mounted at one end thereof between said ears and having a curved head forming a cam, and

teeth located upon said lever between said cam surface and the free end thereof, whereby movement of said lever will initially engage said cam with said rack prior to the engagement of said teeth with said rack. 10

In testimony whereof I affix my signature.

BURROUGH P. MOORE.
